DOLL TOY

Norman Spiegel, 200 5th Ave., New York, N.Y. 10010

Filed July 5, 1973, Ser. No. 376,822

Term of patent 14 years

Int. Cl. D21—01

U.S. Cl. D34—15 AD

FIG. 2

FIG. 1

FIG. 5

FIG. 3

FIG. 4

FIG. 1 is a front elevational view of a doll toy showing my new design;

FIG. 2 is a side elevational view thereof;

FIG. 3 is a top plan view thereof;

FIG. 4 is a bottom plan view thereof; and

FIG. 5 is a rear elevational view thereof.

The design is generally symmetric and the side not shown is substantially identical to the side shown in FIG. 2.

I claim:

The ornamental design for a doll toy, as shown and described.
